RECOVERY OF OXIDATION INHIBITORS

James G. Lillard, Baytown, Tex., assignor, by
mesne assignments, to Standard Oil Develop-
ment Company, Elizabeth, N. J., a corporation
of Delaware

Application October 19, 1950, Serial No. 190,915

7 Claims. (Cl. 196—14.17)

1

The present invention is directed to a method for recovering an oxidation inhibitor from solvent extracts of lubricating oil fractions. More particularly, the invention is directed to the production of an oxidation inhibitor from a solvent extract such as a phenol extract of a Mid-Continent lubricating oil fraction.

The present invention may be described briefly as involving the extraction of a solvent extract such as a phenol extract of a lubricating oil fraction, for example, a Mid-Continent lubricating oil fraction, with a solvent comprising tetrahydrofurfuryl alcohol or with a solvent comprising tetrahydrofurfuryl alcohol and acetone. The phenol extract is admixed with the tetrahydrofurfuryl alcohol solvent under conditions to provide a ratio of tetrahydrofurfuryl alcohol to solvent extract in the preferred range between 1:1 and 4:1. A small amount of water, such as up to about 3% based on the solvent may be added to increase the solvent selectivity. At temperatures in the range from 20° to 100° C. and at pressures ranging from 0 to 25 pounds greater than the vapor pressure of the solvent, the admixture of the solvent extract and solvent forms into two phases, an extract phase and a raffinate phase. The extract phase may be admixed with water, in an amount such as 15% or more by volume based on the extract phase, to adjust the solvency of the tetrahydrofurfuryl alcohol solvent to reject essentially all hydrocarbon. The hydrocarbon extract phase is then water washed to remove traces of remaining solvent. An alternative separation procedure comprises vacuum stripping of the solvent from the hydrocarbon extract phase. The solvent-free hydrocarbon extract phase recovered by either of the above procedures is then suitable for use as an oxidation inhibitor. The oxidation inhibitor may suitably be added to oxidation susceptible lubricating oil fractions such as those obtained from Coastal crudes and those having a naphthene base.

The present invention will be further illustrated by reference to the drawing in which:

Fig. I is in the form of a diagrammatic flow sheet illustrating one mode of practicing the present invention and

Fig. II is in the form of a flow sheet illustrating another mode of practicing the present invention.

Referring now to the drawing, and first to Fig. I, numeral 11 designates an extraction zone which is designed to allow countercurrent extraction of hydrocarbon oils. Extraction zone 11 is understood to include internal baffling equipment such

2

as bell cap trays and contact equipment to allow intimate contact between immiscible liquids. It will be understood that extraction zone 11 is also provided with means for inducing reflux such as are well known in the solvent extraction art. Leading into extraction zone 11 is line 12 by way of which there is introduced thereto a feed which for the purposes of this description is a phenol extract of a Mid-Continent lubricating oil fraction. At times it may be desirable to admix the feed with a paraffinic hydrocarbon before it is introduced into the extraction zone, and such a light hydrocarbon may be introduced through inlet line 10 into the feed passing through line 12. Where a phenol extract of Mid-Continent lubricating oil fraction is used as feed, the paraffinic hydrocarbon may be added thereto in an amount within the range from 10% to 150% based on said phenol extract. There is introduced into extraction zone 11 from storage tank 13 tetrahydrofurfuryl alcohol which is discharged from tank 13 by line 14 and thence by line 15 into extraction zone 11. Conditions are adjusted in extraction zone 11 to maintain a temperature in the range between 20° and 100° C. such that a liquid phase is maintained therein. Pressure may be in the range from 0 to 25 pounds greater than the vapor pressure of the tetrahydrofurfuryl alcohol. Under the conditions in extraction zone 11, which preferably includes the maintenance of a tetrahydrofurfuryl alcohol to phenol extract ratio in the range between 1:1 and 4:1, there is formed therein a raffinate phase and an extract phase. The extract phase by virtue of the nature of the tetrahydrofurfuryl alcohol separates in the lower portion of zone 11 and there may be admixed therewith by way of line 16 controlled by valve 17 a small amount of water such as up to about 3% by volume based on the original tetrahydrofurfuryl alcohol. The water-containing extract discharges from extraction zone 11 by line 18 and may be introduced thereby into a solvent stripping zone 19 which is provided with a heating means illustrated by steam coil 20 wherein temperatures and pressure are adjusted therein to allow the removal from stripper 19 of water by line 21 and tetrahydrofurfuryl alcohol by way of line 22 which returns the tetrahydrofurfuryl alcohol to storage tank 13. The oxidation inhibitor is withdrawn from stripper 19 by line 23 for addition to lubricating oils susceptible to oxidation. Stripping zone 19 is preferably operated at reduced pressures as low as 10 mm. mercury absolute to prevent alcohol degradation.

55

The raffinate phase from extraction zone 11

discharges by line 24 controlled by valve 25 into a stripping still 26 which is similar to stripping still 19 and is provided with a heating means illustrated by coil 27 wherein conditions are adjusted in stripper 26 to remove overhead therefrom water by line 28 and as a side stream tetrahydrofurfuryl alcohol by line 29 which connects into line 22 and allows return of the tetrahydrofurfuryl alcohol to storage tank 13. The stripped raffinate discharges from stripper 26 by line 30 controlled by valve 31 into line 32 and thence into a second extraction zone 33 wherein the raffinate is subjected to re-extraction with acetone introduced thereto by line 34 from acetone storage tank 35.

Extraction zone 33 is similar to extraction zone 11 and is provided with contacting equipment to insure intimate contact between immiscible liquids. Extraction zone 33 is also provided with means for inducing reflux therein. The temperature conditions in extraction zone 33 are in the range between 0° and 75° C. while pressures may range from 0 to 30 pounds per square inch gauge. The amount of acetone which is employed to contact the raffinate in extraction zone 33 may range from a ratio of 1 to 1 to 6 to 1 of acetone to raffinate. Under conditions obtaining in extraction zone 33 a second raffinate and a second extract phase are formed. The secondary extract is withdrawn from extraction zone 33 by line 36 controlled by valve 37 and introduced thereby into a stripping still 38 which, similar to stripping stills 19 and 36, is provided with a heating unit illustrated by coil 39 wherein temperature and pressure conditions are maintained to remove overhead by line 40 which connects into line 41 acetone which is returned by line 41 and branch line 42 to acetone storage 35. The stripped secondary extract discharges from stripper 38 by line 43 controlled by valve 44 and may be recycled to line 12 by way of line 45 controlled by valve 46 or may be discharged in part by opening valve 47 for withdrawal of the intermediate extract from the system.

Alternatively, the extract withdrawn by line 36 from extraction zone 33 may by-pass stripper 38 by closing valve 37 in line 36 and thus allowing the extract to be routed by line 43 controlled by valve 49 to line 45 and thence by line 45 for admixture with the phenol extract in line 12.

The raffinate from secondary extraction zone 33 discharges therefrom by line 50 and is introduced thereby into a stripping zone 51 which, similar to the other stripping stills, is provided with a heating means illustrated by steam coil 52 for adjustment of temperatures and pressures therein to allow removal from stripper 51 by line 41 acetone which is discharged by lines 41 and 42 into acetone storage 35. Since the raffinate withdrawn from extraction zone 11 and second extraction zone 33 contains tetrahydrofurfuryl alcohol, the acetone stripped raffinate is discharged from stripper 51 by line 53 and routed by line 54 controlled by valve 55 into stripping zone 56 which is similar to the other stripping zones and is provided with a heating means illustrated by a steam coil 57 to allow recovery of the tetrahydrofurfuryl alcohol from the raffinate by line 58 which connects into line 22 and conducts the tetrahydrofurfuryl alcohol back to storage tank 13 for re-use in the process. The stripped raffinate is withdrawn from stripper 56 by line 59 controlled by valve 60 for use as may be desired.

As an alternative mode of practicing the invention, a mixture of tetrahydrofurfuryl alcohol and

acetone may be employed as a solvent. Under these conditions the ratio of tetrahydrofurfuryl alcohol to acetone may range up to equal volumes of tetrahydrofurfuryl alcohol to acetone.

For purposes of this description it is assumed that an equal volume mixture of tetrahydrofurfuryl alcohol and acetone is introduced into extraction zone 11 by way of line 15, the acetone being withdrawn from storage tank 61 by line 62 controlled by valve 63. It is to be understood that instead of providing an extra storage tank 61 for acetone that storage tank 35 may be used therefor, but for purposes of this description two storage tanks are provided. In this operation the flow is identical to that described before with the exception that the extract withdrawn by line 18 is discharged by branch line 64 controlled by valve 65 into stripping zone 66 which, like the other stripping zones, is provided with a heating means illustrated by steam coil 67 for adjustment of temperature and pressure conditions therein. When this mode is employed, it is understood, of course, that valve 63 in line 18 is in a closed position. Removed overhead from stripper 66 by line 69 is a stream of acetone which is discharged into storage tank 35 by way of line 42. The acetone-free extract is withdrawn from stripper 66 by line 70 controlled by valve 71 into line 18 and discharged thereby into line 18 for removal of water and tetrahydrofurfuryl alcohol as has been described, and for recovery of the oxidation inhibitor by line 23.

The raffinate may be withdrawn from extraction zone 11 by line 24 and discharged into line 32 for introduction into second extraction zone 33 as has been described, stripping zone 26 being by-passed by closing off valve 25 in line 24 and valve 31 in line 30, valve 72 in line 32 being opened to allow passage of the raffinate directly into extraction zone 33. The flow thereafter is identical with that described before with the extract either by-passing stripper 38 or flowing by line 48 and line 43 and thence by line 45 back into feed line 12.

Although stripping techniques are generally preferred for separation of hydrocarbon extract and solvent, water washing procedures may be employed. The solvent extract, for example, may be admixed with sufficient water, such as 15% or higher based on the extract phase to cause separation of hydrocarbon and solvent. The hydrocarbon layer, after separation, may be water washed to remove traces of solvent remaining therein.

Referring now to Figure II, another mode for practicing the present invention is here illustrated.

In Fig. II, extraction zone 111 corresponds to extraction zone 11 of Figure I. Storage tank 13, used for storing tetrahydrofurfuryl alcohol, and storage tank 62, used for storing acetone, and the lines 14, 15, 62 and valve 63 are identical to the corresponding units of Fig. I. Feed, such as a phenol extract of a Panhandle medium motor distillate, is introduced by inlet line 112 into extraction zone 111. In extraction zone 111, a raffinate phase and an extract phase are formed, the extract separating to the lower portion of zone 111 and being withdrawn through line 118, while the raffinate phase is withdrawn from extraction zone 111 through outlet line 124. Into the stream of extract phase in line 118 there is introduced a low viscosity paraffinic solvent by means of inlet line 114. The paraffinic solvent is added in an amount sufficient to reduce the

viscosity of the extract phase and the two components thoroughly admixed by passing through a suitable mixing device 120. The resultant admixture is withdrawn from mixer 120 through line 21 and has added thereto through inlet line 122 a sufficient amount of water to reduce the solvency of the alcohol in said extract phase and to cause a phase separation into a hydrocarbon phase and an aqueous alcohol phase. Line 121 discharges into settler 123 to allow the phases to separate into a hydrocarbon layer and an aqueous alcohol layer. The aqueous alcohol layer is withdrawn from settler 123 through outlet line 125. The hydrocarbon layer is withdrawn from settler 123 through line 125 and passed into vessel 126, where it is washed with water introduced through inlet line 127 with a spent wash water withdrawn through outlet line 128. The washed hydrocarbon is then passed from washing vessel 126 through line 129 to still 130 where the low viscosity paraffinic solvent is removed as overhead through line 131 and the oxidation inhibitor is withdrawn through line 132.

It will be understood that various types of auxiliary equipment, for example, such as that required for the recovery of solvent, will be desirable in the operation of the method illustrated in Fig. II, but for the purpose of simplifying the drawing and the description, such equipment has not been shown.

From the foregoing description and drawing, it will be seen that several modes of operation are provided wherein an oxidation inhibitor may be recovered by extracting a solvent extract of a lubricating oil fraction with tetrahydrofurfuryl alcohol.

The invention will be further illustrated by the following runs: In the first run 450 volumes of a phenol extract of dewaxed Panhandle medium motor distillate were admixed with approximately equal volumes of tetrahydrofurfuryl alcohol at 24° C. and at atmospheric pressure. Under these conditions an extract layer was separated and diluted with approximately equal volumes (500 parts) of a paraffinic solvent such as petroleum ether to reduce the viscosity of this layer. Water was then added to the admixture of extract and paraffinic solvent in an amount of approximately 15% based on the extract layer. The purpose of the addition of water was to reduce the solvency of the tetrahydrofurfuryl alcohol in the hydrocarbon and cause phase separation. The resulting hydrocarbon layer was then removed, washed with water several times to remove all the tetrahydrofurfuryl alcohol, dried and then distilled to strip therefrom the petroleum ether. Approximately 11 volume percent of an oxidation inhibitor was recovered. Physical and chemical inspection of the phenol extract charged to the operation and the raffinate which was recovered by water washing, drying and stripping similar to the aforementioned technique is compared in the following table with the characteristics of the tetrahydrofurfuryl alcohol extract of the phenol extract.

Table I

Test	Charge Stock	Extract	Raffinate
Refractive Index, n_b^{20}	1.5372	1.5662	1.5258
Carbon, Weight Percent.....	86.9	87.7	86.5
Hydrogen, Weight Percent.....	11.7	11.0	12.0
C/H Weight Ratio.....	7.41	7.98	7.20
Sulfur, Weight Percent.....	0.98	1.3	.....

From the foregoing inspection characteristics it will be seen that the tetrahydrofurfuryl alcohol extract has a much higher carbon-hydrogen weight ratio than either the phenol extract charge stock or the raffinate therefrom.

Various amounts of the tetrahydrofurfuryl alcohol extract were then added to an unstable Coastal lubricating oil and the blends were oxidized under identical conditions in an accelerated laboratory oxidation test. The relative increase in viscosity was taken as a measure of degree of oxidation. The data obtained on these oxidation runs are shown in comparison with similar data obtained for blends of the unstable Coastal lubricating oil with the original phenol extract charge stock and with silica gel extracts of the phenol extract in varying percentages. An oxidation index, which is the product of the ratio of the percent viscosity increase of the sample to the percent viscosity increase of the standard times 100, was calculated for each sample for obtaining relative oxidation characteristics. A lower oxidation index indicates greater resistance to oxidation. These results are given in Table II:

Table II

30	Additive and Concentration	Viscosity at 100° F.		Percent Increase in Viscosity	Oxidation ² Index
		Initial	Oxi-dized		
	None (Standard).....	577	1,650	186	100
	5%—Total Phenol Extract.....	615	950	55	30
	2%—20.6 to 20.9 ¹	577	1,579	173	93

	5%—Tetrahydrofurfuryl Alcohol Extract.....	577	721	25	13
10	Uninhibited Finished Panhandle Medium Motor Oil.....	485	583	20	11

¹ Volume percent extract from silica gel extraction of the phenol extract.

$$^2 \frac{\text{Percent Vis. Increase of Sample}}{\text{Percent Vis. Increase of Standard}} \times 100$$

The oxidation test employed is used to compare the change in properties in oil after subjecting it to fixed oxidation conditions. Usually it is desirable to compare the oil to be tested to a standard oil subjected to the same test. The test is carried out as follows:

Oxidation of an oil sample is carried out in a 200 cc. glass three-necked round bottom flask. The central neck of this flask is 5 cm. long and has an inside diameter of 3 cm. The two opposed side necks are 6 cm. long and 1.5 cm. inside diameter, and are situated at a 30° angle with the central neck, perpendicular to the surface of the spherical flask. The stirrer is a glass rod 0.5 cm. in diameter, entering the flask through a glass tube bearing held in place by a rubber stopper in the central neck, with two glass blades 1.0 cm. long by 0.7 cm. wide welded to opposite sides of the bottom end of the glass rod at a 30° angle with the vertical. The stirrer is driven by a 1750 R. P. M. motor connected to the stirrer by a rubber tubing coupling. The blades of the stirrer are situated about 0.5 cm. from the bottom of the flask and spin in such a direction that their propeller-like action circulates the oil to the bottom of the flask, up along the sides of the flask, back to the center of the flask, and down to the stirrer blades again. A considerable amount of air is sucked down with the descending oil and intimately contacted with

it by the action of the stirrer. A thermometer well 5 cm. long and 1.0 cm. inside diameter is situated in one side of the flask equidistant from the two side arms. During the oxidation the flask is about two-thirds immersed in an oil bath maintained at 375° F. The temperature of the oil in the flask is usually 5 to 10° F. below the temperature of the oil bath.

The oxidation test is carried out in a specially constructed flask by stirring 100 cc. of the sample in the presence of air for sixteen hours at 375° F. At the end of that time the flask is removed from the oil bath and tests obtained on the oxidized oil.

The data presented in Table II show that the tetrahydrofurfuryl alcohol extract is effective in stabilizing an oxidizable Coastal lubricating oil. Furthermore, it will be seen that the oxidizable Coastal lubricating oils, to which the oxidation inhibitor has been added in an amount from 3 to 5% by volume, approach in quality, as measured by the oxidation index, the quality of the original Panhandle medium motor oil from which the phenol extract was obtained.

While one of the examples shows the dilution of the extract layer with a paraffinic solvent, it may be desirable to dilute the solvent extract, such as phenol extract, which is charged to the process with a paraffinic solvent to reduce the viscosity thereof and to facilitate the separation into phases on extraction with tetrahydrofurfuryl alcohol. Illustrative of paraffinic hydrocarbons which may be used to dilute the solvent extract or the tetrahydrofurfuryl alcohol extract are pentane, hexane, heptane, octane, nonane and the like, including isomers thereof. Rather than use a substantially pure paraffinic hydrocarbon, it may be desirable to use a paraffinic hydrocarbon fraction boiling in the range from about 100° F. up to about 300° F.

As another example of the practice of the present invention, a tetrahydrofurfuryl alcohol extract obtained in a single stage extract as described previously was re-extracted with 200 volume per cent of tetrahydrofurfuryl alcohol with 1% by volume of water injection and an extract having a refractive index n_D^{20} of 1.5189 was obtained. Thus, further concentration of the materials of high refractive index was obtained. The yield of the extract was 55 volume per cent of the initial tetrahydrofurfuryl alcohol extract or 6 volume per cent of the total phenol extract.

Runs were also made employing tetrahydrofurfuryl alcohol and acetone in admixtures ranging in concentration from all tetrahydrofurfuryl alcohol to all acetone. Solvent mixtures containing from 20 to 90% by volume of acetone were highly efficient in rejecting materials of lower refractive index into the raffinate, while the tetrahydrofurfuryl alcohol alone with water injection as previously described was highly selective in concentrating highly refractive index materials.

The invention has been described and claimed with respect to extracting a phenol extract of a lubricating oil fraction with a solvent comprising tetrahydrofurfuryl alcohol. While a phenol extract is preferred as the charge stock, other solvent extracts of lubricating oil fractions may be used. For example, furfural extracts of lubricating oil fractions may be used in lieu of a phenol extract. Similarly, extracts of lubricating oil fractions produced by extracting lubricating oil fractions with solvents comprises liquid sulfur dioxide, nitrobenzene, trichloroethylene,

Chlorex, chlorophenol, cresylic acid, pyridine and the like. As a general statement, it may be said that the solvent extract which forms a feed stock for the process of the present invention may be an extract of a lubricating oil produced by solvent extracting same with a solvent which has a preferential selectivity for non-paraffinic constituents. For example, the solvent will take into solution therein substantially non-paraffinic constituents and will reject the substantially paraffinic constituents. It may be further said that the solvent extract of the lubricating oil fraction forming a feed stock of the present invention should be a solvent extract obtained by extracting a lubricating oil fraction with a solvent other than that comprising tetrahydrofurfuryl alcohol.

The nature and objects of the present invention having been completely described and illustrated, what I wish to claim as new and useful and to secure by Letters Patent is:

1. A method for producing an oxidation inhibitor suitable for use in lubricating oil which comprises the steps of admixing a solvent comprising tetrahydrofurfuryl alcohol with a phenol extract of a Panhandle medium motor distillate fraction in an amount and under conditions of temperature and pressure sufficient to cause formation of a second extract phase and a raffinate phase while maintaining a liquid state, separating said phases, removing said alcohol from said second extract phase, and recovering substantially alcohol-free hydrocarbons from said second extract phase suitable for use as an oxidation inhibitor.

2. A method for producing an oxidation inhibitor suitable for use in lubricating oil which comprises the steps of admixing a solvent comprising tetrahydrofurfuryl alcohol with a phenol extract of a Panhandle medium motor distillate fraction in an amount and under conditions of temperature and pressure sufficient to cause formation of a second extract phase and a raffinate phase while maintaining a liquid state, separating said phases, admixing the extract phase with a low viscosity paraffinic solvent in an amount sufficient to reduce the viscosity thereof, adding to the admixture of the extract phase and low viscosity paraffinic solvent a sufficient amount of water to reduce the solvency of the alcohol in said extract phase and to form a hydrocarbon layer and an aqueous alcohol layer, washing said hydrocarbon layer with water to remove alcohol therefrom, removing said low viscosity paraffinic solvent from said hydrocarbon layer by distilling same and recovering an oxidation inhibitor.

3. A method for producing an oxidation inhibitor suitable for use in lubricating oils which comprises the steps of countercurrently contacting in a solvent extraction zone a phenol extract of a Panhandle medium motor distillate fraction with a solvent comprising tetrahydrofurfuryl alcohol in a ratio of alcohol to solvent extract in the range between 1:1 and 4:1 at a temperature in the range between 20° and 100° C. and at a pressure sufficient to maintain liquid phase conditions in said solvent extraction zone to form an extract phase and a raffinate phase, adding sufficient water to said extract phase in said extraction zone to reduce the solvency of said alcohol therein, removing said water-containing extract phase from said solvent extraction zone, and distilling said water-containing extract phase

to remove water and alcohol therefrom and to recover an oxidation inhibitor.

4. A method for producing an oxidation inhibitor suitable for use in lubricating oils which comprises the steps of counter-currently contacting in a solvent extraction zone a phenol extract of a Panhandle medium motor distillate fraction with a solvent comprising tetrahydrofurfuryl alcohol and acetone, said alcohol and acetone being present in said solvent in a ratio no greater than 1:1, in a ratio of solvent to solvent extract in the range between 1:1 and 4:1 at a temperature in the range between 20° and 100° C. and at a pressure sufficient to maintain liquid phase conditions in said solvent extraction zone to form an extract phase and a raffinate phase, adding water to said extract phase in said extraction zone in an amount in excess of about 15% by volume based on said extract phase, removing said water-containing extract phase from said solvent extraction zone and distilling said water-containing extract phase to remove water and alcohol therefrom and to recover an oxidation inhibitor.

5. A method for producing an oxidation inhibitor suitable for use in lubricating oils which comprises the steps of counter-currently contacting in a solvent extraction zone a phenol extract of a Panhandle medium motor distillate fraction with a solvent comprising approximately two volumes of tetrahydrofurfuryl alcohol and one volume of acetone at a temperature of about 25° C. and at atmospheric pressure to form an extract phase and a raffinate phase,

adding water to said extract phase in said extraction zone in an amount in excess of about 15% by volume based on said extract phase, removing said water-containing extract phase from said solvent extraction zone and distilling said water-containing extract phase to remove acetone and aqueous alcohol therefrom and to recover an oxidation inhibitor.

6. A process in accordance with claim 5 in which the phenol extract is admixed with a paraffinic hydrocarbon in an amount in the range from 10% to 150% based on said phenol extract prior to contacting with said solvent.

7. A process in accordance with claim 5 in which the raffinate phase is admixed with acetone under conditions to form a secondary raffinate and a secondary extract phase and in which said secondary extract phase is admixed with said phenol extract.

20 JAMES G. LILLARD.
